Jacob Vosburgh

UNITED STATES PATENT OFFICE.

JACOB VOSBURGH, OF ST. LOUIS, MISSOURI.

BOILER-STAND.

SPECIFICATION forming part of Letters Patent No. 410,947, dated September 10, 1889.

Application filed January 14, 1889. Serial No. 296,375. (No model.)

To all whom it may concern:

Be it known that I, JACOB VOSBURGH, a citizen of the United States, residing at the city of St. Louis, in the State of Missouri, have 5 invented a new and useful Improvement in Boiler-Stands, of which the following is a specification.

My invention relates to improvements in stands for supporting boilers for ranges and 10 stoves in kitchens and elsewhere for family uses; and the objects of my invention are, first, to provide a metallic ring with flange and slots, upon which the boiler rests, and, second, to provide legs so made that their tops 15 penetrate the slots of said ring and at or near their centers cross and interlock with each other, forming a boiler-stand without the use of screws or other fastenings. I attain these objects by the mechanism illustrated in the 20 accompanying drawings, in which—

Figure 1 is a side elevation of my boiler-stand as a whole when the parts are adjusted to each other. Fig. 2 is a top view showing the metallic ring. Fig. 3 is a horizontal section on line 3 3, Fig. 1. Fig. 4 is a vertical section on line 4 4, Fig. 2.

Similar letters refer to similar parts throughout the several views.

The metallic ring A is provided with a flange 30 a', of sufficient width to securely hold the boiler in its seat, and with three depressions a², formed with oblong slots a³, the depressions being equidistant from each other and of sufficient size to admit the heads b' of the legs 35 B, which in adjusting pass through such slots and rest in said depressions, thus securely locking the legs to the metallic ring. The legs are of metal, and, as indicated, are made each with a hook b² on the under side and a 40 projection b³ on the upper side, upon which, when adjusted, the hook rests. The legs are so formed as to cross each other, as shown in Fig. 1, at the point C, and when the hook of each leg forming the cluster rests upon its 45 fellow in front of it, as shown in Fig. 1, the weight of the boiler only tends to make the stand more firm, and there can be no derangement or letting down on any of its parts until the weight has been removed. The three legs

well spread out prevent any lateral play. The 50 legs all being cast from the same pattern insures exactness in all their parts and the holding of the ring perfectly level. The legs are interchangeable and interlocked, so that if one is lost or damaged it can readily be replaced. 55

I prefer to use malleable iron for the legs of said stand because of its toughness; but cast-iron may be used both for the ring and legs, if desired. The legs, as I construct them, 60 are about twenty-three inches long, but may be made longer or shorter, as may be desired.

What I claim as my invention, and desire to secure by Letters Patent, is—

1. A metallic boiler-stand consisting of a 65 ring A and three crossed and interlocked legs B, secured to the ring, substantially as described.

2. The combination of a metallic ring containing three slots with the metallic legs penetrating said slots and crossing each other, and so constructed as to interlock with said ring at their tops and with each other at the point of their crossing, thus forming a stand without the use of screws or other fastenings, substantially as set forth. 70

3. A boiler-stand leg B, constructed with a head b', a hook b² at the under side, and a projection b³ at the upper side, substantially 75 as described.

4. The combination of the ring A, having depressions a² and oblong slots a³, and the crossed and interlocked legs B, having oblong heads b', by which the legs are secured to the ring, substantially as described. 80

5. A boiler-stand consisting of the ring A, formed with a flange a', depressions a², and slots a³, and the legs B, formed with hooks b², projections b³, and heads b', substantially as described. 85

In witness whereof I have hereunto signed my name in the presence of two subscribing witnesses.

JACOB VOSBURGH.
